1
Botanical designation: *Chrysanthemum×morifolium* Ramat.
Cultivar denomination: 'Zanmudeep'.

BACKGROUND OF THE INVENTION

The present invention relates to a new and distinct cultivar of *chrysanthemum* plant, botanically known as *Chrysanthemum×morifolium* Ramat., and hereinafter referred to by the cultivar denomination 'Zanmudeep'. 'Zanmudeep' is a product of a breeding and selection program for pot mums which had the objective of creating new cultivars with a double type inflorescence, a 8 weeks response time and a medium plant height. 'Zanmudeep' is a seedling resulting from a cross of the female parent id 45927 with the male parent id 44279. Plants of the new cultivar 'Zanmudeep' differ from plants of the female parent in inflorescence color. The female parent has pink inflorescences, while those of 'Zanmudeep' are dark purple. Plants of the new cultivar 'Zanmudeep' differ from plants of the male parent in the following characteristics. (1) Plant vigor. And (2) Inflorescence size. (1). Plants of the male parent are less vigorous than those of 'Zanmudeep'. (2) Inflorescences of the male parent are smaller than those of 'Zanmudeep'.

The new and distinct cultivar was discovered and selected as a flowering plant within the progeny of the stated cross by Wilhelmus Bernardus Blom in a controlled environment (greenhouse) in Rijsenhout, The Netherlands in April 2004. The first act of asexual production of 'Zanmudeep' was accomplished when vegetative cuttings were used from the initial selection in June 2004 and propagated further in a controlled environment in Rijsenhout, The Netherlands. The new cultivar has been found to retain its distinctive characteristics through successive propagations, although the phenotype may somewhat vary with variations in environment such as light intensity and temperature.

BRIEF DESCRIPTION OF THE DRAWINGS

The present invention of a new and distinct variety of *chrysanthemum* is shown in the accompanying drawings, the color being as nearly true as possible with color photographs of this type.

(57) **ABSTRACT**

A *chrysanthemum* plant named 'Zanmudeep' characterized by its large sized blooms with dark purple ray florets and prolific branching, and response time of 8 weeks.

3 Drawing Sheets

FIG. 1 shows a plant of the cultivar in full bloom.
FIG. 2 shows the various stages of bloom of the new cultivar.

FIG. 3 shows the various stages of foliage of the new 5 cultivar.

2

DESCRIPTION OF THE INVENTION

The observations and measurements were gathered in May 10 2010 from plants grown in a greenhouse in Rijsenhout, The Netherlands, in a photo-periodic controlled crop under conditions generally used in commercial practice. Three cuttings were planted in a pot with a diameter of 12 cm. The greenhouse temperatures for this crop were at day-time 15 18.degree.C. to 25.degree. C., and at night about 20.degree. C. The photo-periodic response time in this crop was 8 weeks after an average of eight long days. After this long day period growth retardants (Alar) were applied six times in an average dose of 1. 5 gram/liter water until flowering. The plants were 20 observed (directly) during the flowering of this crop. No tests were done on disease or insect resistance or susceptibility. No tests were done on cold or drought tolerance. To show the phenotype as described 'Zanmudeep' can be planted without assimilation lighting (high pressure sodium lamps) between 25 week 50 and week 40 of the next year under greenhouse conditions in the Netherlands. With assimilation lighting (minimum level 2500 lux) it can be planted all year round under greenhouse conditions in the Netherlands.

This new variety produces potmums with large sized 30 blooms with dark purple ray florets. From the cultivars known to inventor the most similar existing cultivar in comparison to 'Zanmudeep' is 'Midnight Time' (U.S. Plant Pat. No. 17,056). When 'Midnight Time' and 'Zanmudeep' are being 35 compared the following difference is noticed: The difference of 'Midnight Time' and 'Zanmudeep' are the following characteristics. (1) Color of the ray florets. And (2) Response Time. (1) Both plant varieties have dark blooms, but the purple ray florets of 'Midnight Time' have a red hue, while those of 'Zanmudeep' are more dark purple. (2) The response Time of 'Midnight Time' is lower than that of 'Zanmudeep'.

The following is a description of the plant and characteristics that distinguish 'Zanmudeep' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum xmorifolium</i> Ramat. 'Zannmudeep'			
<u>Bud</u>			
Size	Medium; cross-section 6 mm, height 4 mm		
Shape	Round	5	
Texture	Smooth	Diameter	1.2 cm
Outside Color	Greyed-green 191A	Reproductive Organs	
Phyllaries		Androecium	Absent
Number	16-18, arranged in 3 rows	Pollen	Not produced
Shape	Elliptic	10 Gynoecium	Present on ray florets
Apex	Acute	Style color	Yellow-green 154C
Base	Truncate	Style Length	3 mm
Margin	Entire	Stigma color	Yellow 7A
Color	Upper surface: Greyed-green 191A Lower Surface: Greyed-green 191B	Stigma Width	1 mm
Length and width	5 mm; 2 mm	Ovary	Enclosed in calyx
Texture	Pubescent	Plant	
Inflorescence		Form	Upright and free branching
Type	Double	Growth rate	Medium
Height	2 cm	Height	18 cm
Diameter	6.5 cm	Width	24 cm
Peduncle length	3 cm	20 Stem Color	Greyed-brown 199A
Peduncle color	Green N138B to N138C	Stem Strength	Strong
Peduncle diameter	2 mm	Stem Brittleness	Not brittle
Peduncle texture	Pubescent	Stem Anthocyanin Coloration	Not observed
Number per branch	Approx. 4-5 inflorescences	Internode length	1 cm
Shelf life	4 weeks	Length of lateral branch	From top to bottom 14 cm
Seeds	Produced in small quantities, ovate, Greyed-brown 199A, length 1.5 mm, diameter 0.8 mm	Lateral branch color	Green 137 C
Fragrance	Faint <i>chrysanthemum</i> odor	25 Lateral branch diameter	3 mm
Color		Lateral branch, attachment	Strong
Center of inflorescence	Immature stage: Red-purple 71A	Branching (average number of lateral branches)	Prolific with 3 breaks after pinching
Color of upper surface of the ray-florets	Mature stage: Red-purple 71A Red-purple 71A to 71B	Response time	8 weeks
Color of the lower surface of the ray-florets	Red-purple 70B	Foliage	
Tonality from Distance	A pot mum with dark purple flowers	30 Leaf color	Upper surface: Green 137A Lower surface: Green N138B
Color of the upper surface of ray-florets after aging of the plant	Purple N77B	Color midvein	Upper surface: Yellow-green 147D Lower surface: Yellow-green 148D
Ray florets		Size	Medium; length 7-8.5 cm, width 4-5 cm
Texture	Upper and lower side smooth	35 Quantity (number per lateral branch)	12
Number	170-180	Shape	Broadly elliptic
Shape	Elliptic	Texture upper side	Sparsely pubescent
Apex	Dentate	Texture under side	Pubescent
Base	Attenuate	Venation arrangement	Palmate
Cross-section	Concave	40 Shape of the margin	Serrated
Longitudinal axis of majority	Straight	Shape of Base of Sinus	Rounded
Length of corolla tube	3-5 mm	Between Lateral Lobes	Diverging
Ray-floret margin	Entire	Margin of Sinus Between Lateral Lobes	
Ray-floret length	2-3 cm	Shape of Base	Acute to truncate
Ray-floret width	0.4-1 cm	45 Apex	Mucronulate
Ratio length/width	Medium	Petiole length	1-2 cm
Disc florets	Absent	Petiole diameter	2 mm
Receptacle		Petiole color	Yellow-green 147D
Color	Yellow-green 145D	50	
Shape	Domed raised		

TABLE 1-continued

Botanical Description of <i>Chrysanthemum xmorifolium</i> Ramat. 'Zannmudeep'		
5 Height	3 mm	
Diameter	1.2 cm	
Reproductive Organs		
Androecium	Absent	
Pollen	Not produced	
10 Gynoecium	Present on ray florets	
Style color	Yellow-green 154C	
Style Length	3 mm	
Stigma color	Yellow 7A	
Stigma Width	1 mm	
Ovary	Enclosed in calyx	
Plant		
15 Form	Upright and free branching	
Growth rate	Medium	
Height	18 cm	
Width	24 cm	
20 Stem Color	Greyed-brown 199A	
Stem Strength	Strong	
Stem Brittleness	Not brittle	
Stem Anthocyanin Coloration	Not observed	
Internode length	1 cm	
Length of lateral branch	From top to bottom 14 cm	
Lateral branch color	Green 137 C	
25 Lateral branch diameter	3 mm	
Lateral branch, attachment	Strong	
Branching (average number of lateral branches)	Prolific with 3 breaks after pinching	
Response time	8 weeks	
Foliage		
30 Leaf color	Upper surface: Green 137A Lower surface: Green N138B	
Color midvein	Upper surface: Yellow-green 147D Lower surface: Yellow-green 148D	
Size	Medium; length 7-8.5 cm, width 4-5 cm	
35 Quantity (number per lateral branch)	12	
Shape	Broadly elliptic	
Texture upper side	Sparsely pubescent	
Texture under side	Pubescent	
Venation arrangement	Palmate	
40 Shape of the margin	Serrated	
Shape of Base of Sinus	Rounded	
Between Lateral Lobes	Diverging	
Margin of Sinus Between Lateral Lobes		
Shape of Base	Acute to truncate	
45 Apex	Mucronulate	
Petiole length	1-2 cm	
Petiole diameter	2 mm	
Petiole color	Yellow-green 147D	

TABLE 2

Differences with the comparison variety when grown side-to-side		
55	'Zannmudeep'	'Midnight Time'
Color ray florets	Red-purple 71A to 71B	Red-purple 61B
Response time	8 weeks	7 weeks

60 I claim:

1. A new and distinct *chrysanthemum* plant named 'Zannmudeep' as described and illustrated.
